UNITED STATES PATENT OFFICE.

CHARLES SANDFORD, OF MADOC, ONTARIO, CANADA, ASSIGNOR OF TWO-
THIRDS TO WILLIAM FEENEY AND ARTHUR COE, BOTH OF SAME PLACE.

LATCH AND LOCK COMBINED.

SPECIFICATION forming part of Letters Patent No. 429,322, dated June 3, 1890.

Application filed April 22, 1889. Serial No. 308,228. (No model.)

To all whom it may concern:

Be it known that I, CHARLES SANDFORD, of Madoc, in the Province of Ontario, Dominion of Canada, have invented certain new and useful Improvements in a Combined Latch and Lock; and I do hereby declare that the following is a full, clear, and exact description of the same, reference being had to the accompanying drawings, forming a part hereof.

10 My invention, which will be hereinafter fully set forth and claimed, relates to that class of combined latch and lock in which the bolt or latch acts by force of gravity.

15 The object of my invention is the construction of a combined latch and lock that shall act without springs, is easily and cheaply manufactured, and affords ample security.

Figure 1 is an elevation of my improved rim-lock, showing the latch-bolt shot locked 20 and night-latched, the night-latch being shown separately in perspective. Fig. 2 is a similar elevation showing the latch-bolt unlocked and retracted and the night-latch off. Fig. 3 is a separate perspective view of the gravity latch-bolt of the same, also the lug on the face-plate to operate the head of the latch-bolt. Fig. 4 is a separate perspective view of the latch-lever of the same. Fig. 5 is a separate perspective view of the tumblers of the same. 25 Fig. 6 is an elevation of a mortise-lock operated by a thumb-latch and in which tumblers are omitted, but may be used. Fig. 7 is a vertical transverse section on line $x-x$, Fig. 6.

30 A a is the casing of the rim-lock, and B is the latch-bolt. The latch-bolt has at its lower part a latch-head b , adapted to project through a slot in the front rim of the casing, is pivoted near the front rim, near its upper end, through an eye b' by a pin C to the casing, 35 provided at little distance from said eye with a lug b'' , projecting from its sunk face and having a lower square shoulder, lower down with an elongated slot b''' , through which projects the pin or post C', which limits the action of the bolt, and to which the case-cover 40 may be screwed. It is further provided opposite the latch-head b with a square-ended elongated slot b'''' , having in its lower edge a square notch b^5 and a square-shouldered recess b^6 on both sides of the tail end. The up-

per part of said latch is made thin to allow the latch-lever to sweep over its face, while the lower part is made thick and heavy, and the rear or tail side made longer and heavier than the front side, so as to cause it to have a 55 tendency to project the latch-head. The outline of the lower edge of the latch is curved to clear the key. The upper edge b^7 of said latch-bolt is made square and for a short length parallel to the upper rim of the casing 60 when the bolt is in its normal or lowermost position.

D is the latch-lever, provided with a hub and facing d , working in the casing and having a square eye adapted to engage and be 65 fettered by the square knob-spindle S, its free end sweeping the recessed face of the upper part of the latch-bolt and adapted to engage the lower shoulder of the lug b'' .

E E are two tumblers having square ends 70 e , connected by a pin E' , passing through and working in the slot b^4 of the latch-bolt, and having square projections or lugs e' fitting the notch b^5 . Their cam ends e'' are adapted to be operated by the cam of the key, and 75 they may be varied to suit different cam combinations. The length of the tumblers is such that when the projection e' is dead on the square rear shoulder of the latch they butt against the rear rim of the casing and 80 prevent the latch from being retracted. A larger number of tumblers may be used.

F is the night-latch, consisting of a double-slotted slide having a finger-piece projecting through a slot f in the upper rim of the casing and adapted to slide snugly upon the facing b^7 and prevent the latch being lifted. The face of the latch-head b may take the usual beveled shape, or its upper edge may be beveled from both sides and slightly 90 curved downward, and be thus worked by a beveled projection n on the face-plate H, as shown in Figs. 2 and 3.

In the mortise-lock, Figs. 6 and 7, A a is the casing; B', the latch-bolt; D', the latch-lever, and G the thumb-latch replacing the knobs and square spindle. In a mortise-lock the night-latch shown in Figs. 1 and 2 is naturally impracticable, and is replaced by a segmental slide F', passing through a 100

slotted plate f' and the square-ended slot b^8 into a slot f'' in the casing A' . In Fig. 7 this latch is shown drawn. The lug b'' is omitted from the latch-bolt and a notch b^9 is provided instead in the upper rear edge of the same, which is engaged by the tip of the latch-lever D' , which is pivoted at the other end by the pin d' and operated by the thumb-latch G , which passes through slots in the casing. This mode of operating the latch-bolt is, however, not essential to mortise-locks, which may be constructed in that respect as shown in Figs. 1 and 2, the thumb-latch being only used in cheap locks. Tumblers may also be used in mortise-locks, as shown in Figs. 1 and 2, and if a large number is used the recessed rear portion of the latch-bolt may be omitted, as shown in Fig. 6.

The lock operates as follows: The latch-bolt B or B' , having its pivotal support high up above and on one side (toward the front) of the center of gravity, has a tendency to swing toward the front and project the latch-head when at rest or in its normal position, being limited in its movement by the post C' and the slot b''' . By turning the knob or knob-spindle the latch-lever D is lifted and bears against the lug b'' , lifting the rear portion of the latch-bolt and swinging the same backward, thus retracting the latch-head, as shown in Fig. 2. When the bolt is in its normal position, or shot, the night-latch F may be slid forward over the face b^7 , thus preventing the bolt being lifted and retracted. Further, when the bolt is shot and the tumblers E are in the position shown in dotted lines in Fig. 1, the projections e' engaging the notch b^5 , the key K may be inserted and turned from left to right, thereby lifting the tumblers and freeing the projections e' from their engagement with the notch b^5 and drawing them rearward against the rear rim of the lock-case and dropping them so that the projections e' engage the rear corner of the bolt.

I claim as my invention—

1. In a combined latch and lock, the combination of a casing having studs C and C' , a latch-bolt B , pivoted at its upper forward end by the eye b' upon the stud C , and having an elongated slot b''' engaging the stud C' , limiting the action of said bolt, also square-ended elongated slot b'''' , opposite the head b , with the notch b^5 and square-ended shoulders, and means for engagement by the latch-lever, a latch-lever adapted to engage the upper rearward part of the latch-bolt, and the tumblers E , having square projections e' , adapted to engage the slot b'''' and notch b^5 , substantially as set forth.

2. In a combined latch and lock, the combination of a casing having studs C and C' ,

a latch-bolt B , having a latch-head b , eye b' , elongated slot b'''' , means for engagement by the latch-lever and upper flat face b^7 , adapted for engagement by the night-latch, a night-latch F , adapted to engage the facing b^7 , and a latch-lever adapted to engage the latch-bolt, substantially as set forth. 65

3. In a combined latch and lock, the combination of the casing $A a$, having studs $C C'$, a latch-bolt B , having latch-head b , eye b' , lug b'' , and slot b'''' , latch-lever D , having facing d , pivoted in the casing and adapted to engage a spindle, and its free end engaging the lug b'' , and spindle S , engaging the eye in said lever, substantially as set forth. 70

4. In a combined latch and lock, the combination of the casing $A a$, having studs $C C'$, a latch-bolt B , having latch-head b , eye b' , lug b'' , slot b'''' , slot b''''' , notch b^5 , and recess b^6 , latch-lever D , with facing d , adapted to engage a spindle, and the free end adapted to engage the lug b'' , spindle S , engaging the eye in said lever, tumbler E , having projections e' , engaging the slot b'''' and notch b^5 , and the key K , substantially as set forth. 75

5. In a combined latch and lock, the combination of the casing $A a$, having studs $C C'$, a latch-bolt B , having head b , eye b' , lug b'' , slot b'''' , slot b''''' , with notch b^5 , recess b^6 , and facing b^7 , night-latch F , adapted to slide in the casing and to engage said facing, latch-lever D , with facing d , spindle S , engaging the eye of said lever, tumbler E , having projections e , engaging the slot b'''' , and the key K , substantially as set forth. 90

6. In a combined latch and lock, the latch-bolt having the head b , eye b' , lug b'' , slot b'''' , slot b''''' , and face b^7 , substantially as set forth. 100

7. In a combined latch and lock, the combination of a casing having studs $C C'$, a latch-bolt having at its lower part a projecting latch-head and an elongated notched slot for the reception of tumblers at the rear thereof, said bolt pivoted at its upper end and at the same side as the head upon the stud C , and having at the rear of said pivot means for engagement by an operating-lever, and having between said pivot and said tumbler-slot an elongated slot engaging the stud C' , limiting the swing of the bolt and adapted to engage a slide, and an operating-lever engaging the upper rear part of said bolt and being itself operated by suitable means, substantially as set forth. 105

In testimony whereof I have signed this specification in the presence of the undersigned witnesses.

CHARLES SANDFORD.
